UNITED STATES PATENT OFFICE.

JOSEPH W. VAUGHN, OF SALEM, MASSACHUSETTS, ASSIGNOR TO THE VAUGHN MOROCCO MACHINE COMPANY, OF PORTLAND, MAINE.

LEATHER-BOARDING MACHINE.

SPECIFICATION forming part of Letters Patent No. 444,172, dated January 6, 1891.

Application filed June 11, 1890. Serial No. 355,049. (No model.)

To all whom it may concern:

Be it known that I, JOSEPH W. VAUGHN, of Salem, in the county of Essex, State of Massachusetts, have invented certain new and useful Improvements in Leather-Boarding Machines, of which the following is a description sufficiently full, clear, and exact to enable any person skilled in the art or science to which said invention appertains to make and use the same, reference being had to the accompanying drawings forming part of this specification, in which—

Figure 1 is an end elevation of my improved boarding-machine; Fig. 2, a front elevation of the same, and Fig. 3 a sectional elevation taken on the end opposite that shown in Fig. 1 to illustrate the reversing mechanism.

Like letters and figures of reference indicate corresponding parts in the different figures of the drawings.

My invention relates, especially, to machines for boarding leather; and it consists in certain novel features, hereinafter fully set forth and claimed, the object being to produce a simpler, cheaper, and more effective device of this character than is now in ordinary use.

The nature and operation of the improvement will be readily understood by all conversant with such matters from the following explanation:

In the drawings, A designates the end pieces or standards of the machine. A horizontally-arranged cylinder or drum B is journaled centrally in said standards by means of a shaft 35 b. A horizontal arm d is formed centrally on the outer face of each standard, and is provided with laterally-projecting lugs f. A block i is disposed between each set of lugs f, and is held in position by guide-spindles g, turned therein and passing vertically and loosely through openings in said lugs. In each set of blocks i a horizontal rod h is fitted to slide longitudinally. Chains j, respectively secured to the forward ends of the rods h, 40 pass over pulleys m on the arms d and are fastened to a foot-treadle k, mounted on said standards. A shell D, approximately semi-circular in end elevation, partially encircles the drum B and is secured to the rear ends of the rods h. The cylinder B is covered or faced 45 with cork, and the shell D may be lined there-

with or with other suitable substances. Diagonally arranged braces or arms p connect the ends of said shell with the sliding rods h. A stiff coiled spring x is mounted on each 55 sliding rod between the front block i and the adjacent brace p, said springs acting expansively to force the shell away from the drum. The upper edge of the shell is grooved longitudinally at q, and a clamp r is pivoted to the 60 top of the shell to enter said groove, the purpose of said clamp being to secure an edge of the skin to the shell. A horizontal rod t is secured to the upper edge of the shell. A hand-lever v, pivoted by means of a rod w in 65 the standards, has one arm secured to said rod t. A short lever y on the pivot-rod w connects it with the shell-rod t, the purpose of said levers being to throw the upper edge of the shell away from the drum sufficiently to 70 insert the hide. A large gear C is mounted on the drum-shaft. A horizontal shaft 15 is journaled in the top of the standards and bears a driving-pulley. A gear 16 is mounted on said shaft. A sector 17 is mounted loosely 75 on said shaft and may be swung vertically by means of a hand-rod 18, said rod being fitted to enter a notched rail on the standard to hold the sector in position. An intermediate gear 19 is journaled on the sector and meshes with 80 the gear 16 and main gear C, whereby the drum may be caused to rotate in one direction. A small gear 20 is journaled on the sector and meshes with the gear 18 thereon. By moving the sector so that said gear 20 will mesh 85 with the main gear C and the gear 18 be disengaged therefrom the drum may be rotated in the opposite direction.

In the use of my improvement the skin to be boarded is secured by one edge to the shell 90 in the clamp r. The shell is elevated or thrown backward slightly by means of the lever v to enable the skin to be folded under the edge of said shell, the body of the skin lying on the front of the drum. The drum 95 rotating from right to left, as viewed in Fig. 1, the skin is carried thereby under the shell. The operator depressing the treadle k draws forward the sliding rods h against the pressure of the springs x. The arms or braces p, 100 being secured to said rods and to the shell, draw said shell tightly and evenly against the

drum, which compresses the skin firmly between them. The cork facing prevents the skin from slipping, and the effect thereon is practically the same as the hand operation in common use. When the skin is thus passed its full length between the drum and shell, the operator, by depressing the lever 18 and throwing the gear 20 into engagement with the main gear C, reverses the movement of the drum, the skin being returned in its folded condition therewith. Springs 25, disposed around the guide-screws g, between the lugs f and blocks i, cushion said blocks and permit vertical play of the sliding rods h.

I do not confine myself to the means shown for reciprocating the drum, as any mechanism suitable for the purpose may be employed. Nor do I confine myself to using the treadle mechanism for forcing the shell into engagement with the drum, as a system of levers will effect the same result. The drum may also be made stationary and the shell readily fitted to reciprocate through an arc over the drum. Said drum may not of necessity be cylindrical in form, as a partial drum or one segmental in end elevation may be employed, the size of the skins seldom requiring a complete revolution of the drum or shell to work them. It will be understood that the same effect may be produced on the leather by passing it, in the manner described, between a flat bed and a reciprocating platen; but by employing my rotary drum and shell the operation, while

equally as effective, is much more rapid and the machine occupies a much less floor-space. 35

Having thus explained my invention, what I claim is—

1. In a leather-boarding machine, the combination of two end standards, a cylinder journaled therein, rods sliding in supports on said standards, an arc-shaped adjustable shell adapted to operate in conjunction with the periphery of said cylinder, provided with arms at its ends having eyes through which said rods pass, means for oscillating said cylinder, means for sliding the shell on said rods toward the cylinder, and means for clamping the leather, substantially as set forth. 40

2. In a leather-boarding machine, the combination of two end standards, a drum journaled therein, means for oscillating said drum, vertical guide-spindles supported in said end standards, blocks on said spindles, horizontal rods supported in said blocks, springs on said guide-spindles for cushioning said blocks, adapted to operate in conjunction with the periphery of said cylinder, provided with arms supported by said rods, springs for throwing out the shell, means for sliding the shell on rods toward the cylinder, and means for clamping the skins, substantially as set forth. 45 50 55 60
